UNITED STATES PATENT OFFICE.

ADOLF H. SCHAFFERT, OF YOUNGSTOWN, OHIO, ASSIGNOR TO THE GENERAL FIRE-PROOFING COMPANY, OF YOUNGSTOWN, OHIO, A CORPORATION OF OHIO.

METAL STRUCTURE FOR DOORS AND ANALOGOUS USES.

1,015,212.

Specification of Letters Patent. Patented Jan. 16, 1912.

Application filed June 2, 1911. Serial No. 630,963.

To all whom it may concern:

Be it known that I, ADOLF H. SCHAFFERT, a citizen of the United States, residing at Youngstown, in the county of Mahoning 5 and State of Ohio, have invented certain new and useful Improvements in Metal Structures for Doors and Analogous Uses, of which the following is a specification.

This invention relates to the general subject of metal office furniture of the fireproof type, and has particularly in view a metal structure belonging to this class, which possesses special utility in the manufacture of doors for safes and analogous purposes.

To this end the invention contemplates a metal door structure or the like constructed of a minimum number of parts, while at the same time being readily manufactured and assembled, and possessing exceptional strength and reinforcement throughout, thus particularly adapting the structure for the doors of safes.

With these and other objects in view which will more readily appear to those familiar with the art as the nature of the invention is better understood, the same consists in the novel construction, combination, and arrangement of parts hereinafter more fully described, illustrated and claimed.

The essential features of the invention are necessarily susceptible to structural change without departing from the scope thereof, but the preferred embodiment is shown in the accompanying drawings, in which—

Figure 1 is a perspective view of a metal door structure, of the safe type, constructed in accordance with the present invention. Fig. 2 is a cross sectional view on the line 2—2 of Fig. 1. Fig. 3 is a vertical sectional view of the metal door structure, the line of section thereof being indicated by the line 3—3 on Fig. 4. Fig. 4 is a vertical sectional view on the line 4—4 of Fig. 3. Fig. 5 is a perspective view of one of the wall plates of the door structure, said view also including sectional perspective details of the top and side edge portions of the said wall plate. Fig. 6 is a similar view of the other wall plate of the structure, said view also including sectional perspective details of the bottom and side edge portions of the said wall plate.

Like references designate corresponding parts in the several figures of the drawings.

55 The improved metal structure claimed

herein presents a hollow body of substantially a rectangular form, and preferably having the general design and characteristics of a safe door. However, irrespective of the precise design of the body of the structure, the latter essentially consists of two parts or sheets of metal adapted to be assembled and interlocked in the novel manner now to be explained.

Referring particularly to the drawings, it will be observed that the body of the metal structure primarily consists of a pair of spaced metal wall plates 1 and 2 arranged in parallel relation and having interlocking flanged edge portions at the top and bottom and sides thereof. While it is of course immaterial as to which of the metal wall plates constitute the outer or inner wall of the structure, for convenience in understanding the same, the plate 1 may be designated as 60 the outer wall plate, and the plate 2 as the inner wall plate.

The two wall plates 1 and 2 are preferably of the same general configuration, that is, of a rectangular form, and according to 65 the present invention, the wall plate 1 is formed at one side edge with a laterally offset inturned stepped flange element 3, while at its directly opposite side edge the same wall plate 1 has projected from the same side 70 thereof as the element 3, an outwardly projecting stepped flange element 4, which latter element may be said to be outturned as distinguished from the inturned flange element 3. In addition to the side stepped 75 flange elements 3 and 4, the outer wall plate 1 is provided at the top and bottom edges thereof with the inturned and laterally offset stepped flange elements 5 and 6 respectively, the said lower one 6 of said flange 80 elements having a greater number of steps or shoulders than the said upper flange element 5, as plainly appears in Fig. 4 of the drawings, as well as in Fig. 6 of the drawings.

The inner wall plate 2 is correspondingly constructed. That is to say, the said inner wall plate 2 is provided at one side edge with a laterally offset stepped flange element 7 that is adapted to slidably interlock 90 with, and register inside of, the side flange element 3 of the outer plate 1. At its opposite side edge the inner wall plate 2 is provided with an inturned hook-flange 8, laterally offset, and slidably interlocking with, 95

and over the outside of the outturned flange element 4 of the lower plate 1. This construction is plainly shown in Fig. 2 of the drawings.

5. Besides the side flange elements 7 and 8, the inner wall plate is provided at its top edge with a laterally offset stepped top flange element 9 adapted to engage over and form a complement of the upper flange element 5 of the outer wall plate 1. Also, at its bottom edge the inner wall plate 2 is formed with a laterally offset bottom flange element 10 adapted to fit inside of, and interlock with, the lower flange element 6 of the outer wall plate 1.

In assembling the two wall plates 1 and 2, constructed as above described, the inner wall plate 2 is slid downwardly upon the inner face of the wall plate 1 to bring the 20 parts into the relation set forth. In this operation the inside stepped flange element 7 of the inner plate 2 passes into position through the combined clearance and guiding slot 11 which pierces the upper flange element 5 of the outer wall plate 1. Also, a longitudinally arranged interior brace 12 carried by the wall plate 2 is carried by the latter into its position between the two plates by said brace passing through the 25 combined clearance and guiding slot 13 piercing the upper flange element 5 of the outer plate 1. With the parts assembled as described, adjoining faces may be soldered, riveted or otherwise rigidly connected.

30 35 I claim:

1. A metal structure of the class described, comprising a pair of spaced metal wall plates, the outer wall plate being provided at one side edge with an inturned stepped flange element, at its opposite side

edge with an outturned stepped flange element, and with inturned stepped flange elements at its top and bottom edges, and the inner of said wall plates being provided at one side edge with a flange engaging inside of the inturned flange element of the outer plate, at its opposite side edge with a flange engaging over the outturned flange element of the outer plate, and at its top and bottom edges provided with flange elements which respectively engage over the top flange and inside of the bottom flange of the outer wall plate.

2. A metal structure of the class described, comprising a pair of spaced metal wall plates, the outer wall plate being provided at its side and top and bottom edges with stepped flange elements, and having combined clearance and guiding slots in the top flange element, and the inner of said wall plates carrying an interior brace piece and provided at one side edge with a stepped flange engaging inside of the flange at one side edge of the outer plate, at its opposite side edge with an inturned hook flange engaging over the flange at the other side edge of the outer plate, and at its top and bottom edges with stepped flange elements which respectively engage over the top flange and inside of the bottom flange of the outer wall plate, one side flange and said brace piece of the inner plate being adapted to pass through said slots in the assembling operation.

In testimony whereof I hereunto affix my signature in the presence of two witnesses.

ADOLF H. SCHAFFERT.
